ATTORNEY

UNITED STATES PATENT OFFICE.

ARTHUR A. KRAEUTER, OF NEWARK, NEW JERSEY.

DESIGN FOR A GOLF-PUTTER HEAD.

57,980.

Specification for Design.

Patented May 24, 1921.

Application filed March 9, 1921. Serial No. 450,973. Term of patent 14 years.

To all whom it may concern:

Be it known that I, ARTHUR A. KRAEUTER, a citizen of the United States, residing at Newark, in the county of Essex and State of New Jersey, have invented a new, original, and ornamental Design for Golf-Putter Heads, of which the following is a specification, reference being had to the accompanying drawing, forming part thereof.

The figure is a plan view of a golf putter head showing my new design.

I claim:

The ornamental design for a golf putter head as shown.

ARTHUR A. KRAEUTER.

Witnesses:

C. W. HILL,
A. W. BOTELER.
